UNITED STATES PATENT OFFICE.

JOHN F. DORNFELD, OF CHICAGO, ILLINOIS.

BOILER.

1,282,775.

Patented Oct. 29, 1918.

Application filed October 14, 1916. Serial No. 125,560.

To all whom it may concern:

Be it known that I, JOHN F. DORNFELD, a citizen of the United States, residing at Chicago, in the county of Cook and State of Illinois, have invented certain new and useful Improvements in Boilers, of which the following is a specification.

This invention relates particularly, although not exclusively, to small boilers adapted for use in connection with isolated electric-lighting plants and other installations requiring a comparatively small amount of power.

One of the objects of this invention is to produce a boiler from which scale and sediment may be readily removed, and which shall not be rendered seriously inefficient by the presence of considerable quantities of sediment and scale.

Another object of the invention is to produce a construction which will facilitate the circulation of the water.

A further object is to provide a boiler comprising a water container formed of cast metal and providing a relatively large amount of heating surface.

A further object is to provide a water container and water circulating system which shall be particularly adapted to the use of fluid fuel.

In the accompanying drawings, Figure 1 is a vertical central sectional view of a boiler embodying the features of my invention. Fig. 2 is a horizontal view of the primary water container showing also in section the casing that incloses said water container and two fluid fuel nozzles. Fig. 3 is a sectional view taken in the plane of dotted line 3—3 of Fig. 2. Fig. 4 is a section on dotted line 4—4 of Fig. 2. Fig. 5 is a sectional view of the header and pipe connections from the annular water containers.

The boiler may include an inclosing casing of any suitable form and construction, as, for example, the vertical casing 1 shown in the drawings. The upper portion 1^a of the casing may be made removable from the lower portion in any suitable manner. In the lower portion of the casing 1 is a horizontal partition 2 which with the adjacent portions of the casing 1 constitute a circular casing that incloses what may be termed the primary water container 3. As shown in Fig. 2, the water container 3 partakes of the general form of the letter S and is arranged in horizontal position. It is divided

by a horizontal partition 4 into an upper and a lower water chamber, which chambers communicate with each other by means of ports 5 extending through the partition 4 at the ends of the container. Said container has a central inlet 6 in its lower side and a central outlet 7 in its upper side. If desired, other suitable baffle means may be interposed between the inlet and the outlet instead of the partition 4. The inlet 6 is connected by means of a short pipe or nipple 8 with a settling chamber 9 located directly beneath the primary water container 3. The settling chamber 9 has a blow-off cock 9^a.

A tube 10 is connected to the primary water container 3 in alignment with and in communication with the outlet 7. The tube 10 supports and communicates with a main water container comprising a plurality of annular concentric portions or sections arranged one inside another. The central annular section is designated by the number 11 and it is or may be cast integral with the tube 10, said tube extending centrally through the section 11. The section 11 is spaced away from the tube 10 so as to form an annular passage 12 for the products of combustion. The lower end of the section 11 communicates with the tube 10 through one or more tubes or passages 13.

At its upper end the central section 11 is provided with an annular outwardly extending flange 14 which underlies and supports an annular inwardly extending flange 15 upon the upper end of the annular section 16 of the main water container. The flanges 14 and 15 may, if desired, be secured together in any suitable way, as, for example, by means of screws 17. The sections 11 and 16 are spaced apart to form an annular passage 18 for the products of combustion.

The annular section 16 is provided at its upper end with an annular outwardly extending flange that underlies and supports an inwardly extending annular flange upon the annular section 19 of the main water container. The sections 16 and 19 are spaced apart to form an annular passage 20 for the products of combustion.

The annular section 19 has at its upper end an annular outwardly extending flange that supports an inwardly extending annular flange upon the outermost annular section 21 of the main water container. The sections 19 and 21 are spaced apart so as to

provide a passage 22 for the products of combustion. The annular passages 12, 18, 20 and 22 communicate with each other at their upper ends through the medium of a 5 suitable number of short tubes or passages 23.

The outer wall of the section 21 is extended above the other sections and is attached to a dome 24 that defines a steam and 10 water chamber 25 above the annular concentric sections of the main water container.

A steam pipe 26 is connected to said chamber. The tube 10 may, as herein shown, extend above the annular sections 11, 16, and 15 19 so as to conduct water to the steam and water chamber 25. If desired, the dome 24 may be connected to the upper end of the tube 10 by means of a screw 27. The annular water-containing sections 11, 16, 19 20 and 21 communicate at their upper ends with the steam and water chamber 25.

The partition 2 has a central opening 28 to permit products of combustion to pass upwardly from the chamber that incloses the 25 primary water container 3. The water-containing section 16 extends below the section 11 and relatively close to the partition 2 so as to surround the opening 28 and compel the products of combustion to pass upwardly 30 through the annular passages 12 and 18. If desired, a ring 29 of any suitable material may be loosely set upon the partition 2 directly beneath the water-containing section 16.

35 The annular passages 20 and 22 communicate with each other at their lower ends. After going through said passages the products of combustion pass upwardly around the outermost water-containing section 21 40 to a chamber 30 above the main water container and thence through an opening 31 into a chamber 32 and thence to an outlet flue 33.

The lower ends of the annular water-containing sections 16, 19 and 21 are connected 45 to the inlet 6 of the primary water container. Herein I have shown pipes 34, 35 and 36 leading from the sections 16, 19 and 21, respectively, and connected to a header 50 37 which header is connected to a tube 38 which in turn is connected to the settling chamber 9. The header 37 is provided with a cleaning opening 39 in alinement with the tube 38, said opening being normally closed 55 by means of a screw plug 40.

Water may be supplied to the boiler in any suitable manner. Herein I have shown a supply pipe made in two sections 41 and 42, said sections being screwed into the wall 60 of the settling chamber 9 in communication with each other. The section 42 extends within the tube 38 and is provided with a fitting 43 that directs the water into the tube 38 in the direction which water is circulating 65 through said tube. The water supply may

be of any suitable character. Herein is shown a pump 44 arranged to discharge water into the pipe 41.

If desired, a suitable form of feed-water heater may be employed. Herein is shown 70 a water container 45 located in the chamber 32 and provided with an inlet pipe 46 and an outlet pipe 47. Said outlet pipe is connected to the intake of the pump 44 by means of a pipe 48. 75

Any preferred means of supplying fuel may be employed. Herein are shown two nozzles 49 (Fig. 2) located in a horizontal plane and extending into the spaces between the ends of the S-shaped primary water container and the adjacent portions of said container. As indicated in the drawings, the primary water container 3 is spaced away from the top and bottom walls of its inclosing casing so as to permit the products of combustion to flow all around said water container. The nozzles are arranged to discharge fluid fuel in opposite directions. Each nozzle is open at one side so as to allow the fuel and flame to be discharged toward the periphery of the casing that incloses the primary water container. The opposite side of the nozzle is closed and is provided with upwardly and downwardly extending flanges 50 which extend into contact with the upper and lower walls of the chamber that incloses the primary water container, thus preventing the injected materials from being discharged at that side of the nozzle and thus preventing one nozzle 90 from blowing out the flame issuing from the other nozzle. 95

In practice, water is supplied to the pipe 46 and forced into the boiler by means of the pump 44. The fuel may be crude oil, 105 distillate or any other suitable kind of liquid or fluid fuel. When oil is used it may be carried through the nozzles 49 by means of jets of steam or compressed air.

Sediment which collects in the chamber 9 and adjacent portions of the boiler may be blown out through the cock 91. The boiler is of such construction that, when desired, it may be readily taken apart for cleaning or replacement. The upper section 110 1^a of the casing 1 may be removed to provide access to the main water container. After the dome 24 has been taken off, brushes or other cleaning implements may be inserted into the upper ends of the annular water containers 16, 19 and 21, and scale 115 and sediment thus removed. 120

I claim as my invention:

1. A boiler having an S-shaped water container arranged in horizontal position 125 and having an inlet and an outlet, and fluid-fuel nozzles projecting horizontally into the spaces formed between the end portions and the central portion of the S-shaped container. 130

2. A boiler having, in combination, a water container comprising a plurality of annular concentric portions communicating with each other at their upper ends, a header 5 below the container, means connecting the lower ends of each of said portions of the container with said header, a central conducting member communicating with the lower end of one of the annular portions and 10 having a sediment chamber in its lower end, and a pipe connecting said conducting member with the header.

3. A boiler having, in combination, a water container comprising a plurality of 15 annular concentric portions, said portions communicating at their upper ends, means connecting the lower ends of said concentric portions, water-supply means communicating with said connecting means, and a settling 20 chamber communicating with said connecting means and in near proximity to said water-supply means.

4. A boiler having, in combination, a casing, a partition having a central opening 25 providing two communicating chambers within said casing, the water container in one of said chambers comprising two annular concentric portions communicating at their upper ends, said concentric portions 30 being spaced apart to provide an annular passage for products of combustion, a central vertical tube communicating with the lower end of the central annular portion, a primary water container directly below the 35 other water container and in the other chamber, said primary container having an outlet which communicates with the lower end of the vertical tube, means forming a passage connecting the lower end of the outer 40 annular portion with the inlet of the primary water container, means for heating said primary container, said heating means discharging products of combustion through 45 said central opening into said annular chamber, a water supply pipe communicating with the above mentioned passage leading to the inlet for the primary water container, and a sediment chamber connected to the last 50 mentioned passage.

5. A boiler having, in combination, a casing, a water container therein comprising two annular concentric portions communicating at their upper ends with each other, said concentric portions being spaced apart to 55 provide an annular passage for products of combustion, a partition within the casing having a central opening, heating means discharging products of combustion through said central opening into the space adjacent 60 to the central annular portion of the water container, the other annular portion being extended below the central annular portion, and water-conducting means connecting the lower ends of said annular portions including a header and settling tank.

6. A boiler having, in combination, a casing, a water container therein comprising two annular concentric portions communicating at their upper ends with each other, said concentric portions being spaced apart 70 to provide an annular passage for products of combustion, a partition within the casing having a central opening, heating means discharging products of combustion through said central opening into the space adjacent 75 to the central annular portion of the water container, the other annular portion being extended below the central annular portion, and water-conducting means connecting the lower ends of said annular portion.

7. A boiler having, in combination, a casing, a water container therein comprising two annular concentric portions communicating with each other, water and steam connections for said container, said 80 concentric portions being spaced apart to provide an annular passage for the products of combustion, a partition in said casing beneath said container and having a central opening, heating means discharging 85 products of combustion through said central opening into the space adjacent the central annular portion of the water container, the other annular portion being extended below the central annular portion, and an outlet for the products of combustion around 90 the outermost annular container.

8. A boiler having, in combination, a casing, a water container therein comprising two annular concentric portions communicating with each other, water and steam connections for said container, said concentric portions being spaced apart to 100 provide an annular passage for the products of combustion, a partition in said casing beneath said container and having a central opening, heating means discharging products of combustion through said central opening into the space adjacent the central annular portion of the water container, the other annular portion being extended below the central annular portion, and a sealing ring between the other annular portion and the partition. 105

9. A boiler having, in combination, a casing, a water container therein comprising a plurality of annular concentric portions communicating with each other, means for supplying water to the central annular portion, a steam outlet for the water container, 110 said concentric portions being spaced apart to provide annular passages for products of combustion, the upper portions of said passages being connected together, a partition in said casing beneath said water container having 115 a central opening, heating means discharging products of combustion through said central opening into the space adjacent to the central annular portion of the water container, and an outlet for the products of 120

125

130

- 24
- combustion within the casing and around the outermost annular portion of the water container.
10. A boiler having, in combination, a water container comprising a plurality of annular concentric sections, each having at its upper end an annular outwardly extending flange that underlies an annular inwardly extending flange on the next outer section, and means for supporting the central annular section. 70
11. A boiler having an S-shaped water container arranged in horizontal position, said container having a horizontal partition dividing the container into an upper and a lower chamber, the lower chamber having a central inlet and the upper chamber having a central outlet, said partition having ports which connect the two chambers near the ends of the S-shaped container. 75
12. A boiler having an S-shaped water container arranged in horizontal position, said container having a horizontal partition dividing the container into an upper and a lower chamber, the lower chamber having a central inlet and the upper chamber having a central outlet, said partition having ports which connect the two chambers near the ends of the S-shaped container, and fluid-fuel nozzles projecting horizontally into the spaces formed between the end portions and central portion of the S-shaped container. 80
13. A boiler having an S-shaped water container arranged in horizontal position and having a central inlet and a central outlet, baffle means interposed between said inlet and said outlet, and fluid-fuel nozzles projecting horizontally into the spaces formed between the end portions and central portion of the S-shaped container. 85
14. A boiler having an S-shaped water container arranged in horizontal position and having an inlet and an outlet, fluid-fuel nozzles projecting horizontally into the spaces formed between the end portions and central portion of the S-shaped container, and a circular casing inclosing the container, said nozzles extending in opposite directions and serving to direct the fuel and products of combustion toward the periphery of said casing. 90
15. A boiler having in combination, a primary water container arranged in horizontal position and having two sections communicating with each other, one of said sections having an inlet and the other section having an outlet, a secondary container above said primary container and comprising a plurality of annular concentric portions communicating with the inlet and outlet of the primary container, and means for heating said containers. 95
16. A boiler having, in combination, a casing, a primary container arranged in horizontal position and having an inlet and
- an outlet, a secondary container above the primary container and comprising a plurality of spaced upright annular concentric portions communicating with the inlet and outlet of the primary container, and means for successively heating said containers, said means being located adjacent said primary container and discharging products of combustion into the spaces between said concentric portions of the secondary container. 100
17. A boiler having, in combination, a water container comprising a plurality of upright annular concentric portions, said portions communicating with each other at their upper ends, a central vertical tube communicating with the lower end of the central annular portion, and a horizontally disposed primary water container below the first mentioned container and having an outlet which communicates with the lower end of said vertical tube and an inlet which communicates with the lower end of the other annular portion to complete a circuit. 105
18. A boiler having, in combination, a water container comprising a plurality of upright annular concentric portions having open upper ends, means providing a steam and water space above said annular portions, a central vertical tube communicating with the lower end of the central annular portion and arranged to discharge water into said water and steam space, and means connecting the other annular portion with the lower portion of said tube to complete a circuit. 110
19. A boiler having, in combination, a water container comprising a plurality of upright annular concentric portions communicating with each other, means for supplying water to the central annular portion, a steam outlet for the water container, said concentric portions being spaced apart to provide annular passages for products of combustion and the upper portions of said passages being closed, heating means discharging products of combustion into the space adjacent to the central annular portion of the water container, and an outlet for the products of combustion around the lower end of the outermost annular portion of the water container. 115
20. A boiler having, in combination, a water container comprising inner, outer and intermediate annular concentric portions, said portions communicating with each other at their upper ends, a central vertical tube communicating with the inner annular portion, and means connecting the lower end of the outer annular portion with the lower portion of said tube to complete a circuit. 120
21. A boiler having, in combination, a water container comprising a plurality of upright annular concentric portions, said portions communicating with each other at their upper ends, a central vertical tube com- 125
- 130

- 5 municating with the lower end of the central annular portion, and means connecting the lower end of the other annular portion with the lower portion of said tube, said means having a clean-out opening therein.
22. A boiler having, in combination, a water container comprising a plurality of upright annular concentric portions, means forming a steam chamber with which the 10 upper ends of said portions communicate and means extending below the container and including a primary water container connecting the central annular portion with the lower end of the other annular portion.
- 15 23. A boiler having, in combination, a water container comprising a plurality of annular concentric portions communicating with each other, a water and steam space in the upper portion of said container, said 20 concentric portions being spaced apart to provide annular passages for products of combustion, means for closing the upper ends of said passages, heating means discharging products of combustion into the 25 space adjacent to the central annular portion of the water container, and an outlet for the products of combustion around the lower end of the outermost annular portion of the water container.
- 30 24. A boiler having, in combination, a water container comprising a plurality of upright annular concentric portions, said portions communicating with each other at their upper ends, and means extending below the water container and connecting the lower end of the central annular portion with the lower end of the other annular portion, said means having a clean-out opening therein.
- 35 25. A boiler having, in combination, a water container comprising two upright annular concentric portions, means forming a steam and water space communicating with the upper ends of said concentric portions, 40 said concentric portions being spaced apart to provide an annular passage for products of combustion, a central vertical tube communicating with the lower end of the central annular portion and also arranged to 45 conduct water into said water and steam space, a primary water container below the first mentioned container and having an outlet which communicates with the lower end of the vertical tube, means forming a 50 passage connecting the lower end of the outer sage connecting the lower end of the outer
- annular portion with the inlet of the primary water container, means for heating said primary water container, said heating means discharging products of combustion into said annular passage, and a water supply pipe communicating with the above mentioned passage leading to the inlet of the primary water container. 60
26. A boiler having, in combination, a water container comprising two annular 65 concentric portions, means forming a steam and water space communicating with said annular concentric portions, said concentric portions being spaced apart to provide an annular passage for the products of combustion, means for closing the upper ends of 70 said passage, a central vertical tube communicating with the central annular portion and arranged to conduct water into said water and steam space, a primary water container below the first mentioned container and having an outlet which communicates with the vertical tube and an inlet, means forming a passage connecting the outer annular portion with the inlet of the primary 75 water container, means for heating said primary water container, said heating means discharging products of combustion into said annular passage, and a water supply pipe arranged to discharge into the above 80 mentioned passage leading to the inlet of the primary water container.
27. A boiler having, in combination, a water container comprising two upright annular concentric portions communicating at 85 their upper ends with each other, said concentric portions being spaced apart to provide an annular passage for products of combustion, means for closing the upper end of said passage, a central vertical tube communicating with the lower end of the central annular portion, a horizontally-disposed 90 primary water container below the first mentioned container and having an outlet which communicates with the lower end of the vertical tube and an inlet which communicates with the lower end of the outer annular portion, and means for heating said primary water container, said heating means discharging products of combustion into 95 said annular passage to heat the other water container. 100
- 105

In testimony whereof, I have hereunto set my hand.

JOHN F. DORNFELD
